PASTE DISPENSER HAVING A BASE AND A
ROLLER ADAPTED TO COMPRESS A COL-
LAPSIBLE TUBE

Anton Yantzer, Rapid City, S. Dak.

Application March 4, 1952, Serial No. 274,698

2 Claims. (Cl. 222—101)

1

This invention relates to paste dispensers and more particularly to a device for dispensing paste, such as tooth paste, from collapsible tubes.

It is among the objects of the invention to provide an improved paste dispenser which is adapted to be mounted on a wall, such as the wall of a bath room, and holds a collapsible tube of paste, such as tooth paste; which firmly supports the collapsible tube in inverted position and provides manually operated means for forcing the paste contents of the tube in selected quantities out of the tube neck disposed at the bottom of the dispenser; which provides means securely closing the tube neck when the dispenser is not in use; which is effective to force substantially all of the contents from a collapsible tube; and which is simple and durable in construction, economical to manufacture, easy to use, and neat and attractive in appearance.

Other objects and advantages will become apparent from a consideration of the following description and appended claims in conjunction with the accompanying drawings wherein:

Figure 1 is a top plan view of a paste dispenser illustrative of the invention;

Figure 2 is a side elevational view of the dispenser;

Figure 3 is a front elevational view of the dispenser;

Figure 4 is a longitudinal cross sectional view on the line 4—4 of Figure 3;

Figure 5 is a longitudinal cross sectional view on the line 5—5 of Figure 4; and

Figure 6 is a transverse cross sectional view on the line 6—6 of Figure 4.

With continued reference to the drawings, the numeral 10 generally indicates a base of unitary construction and of elongated, rectangular shape having legs 11 and 12 projecting perpendicularly from one side, one at each end thereof and extending transversely of the base. The base also has a plurality of spaced apart, undercut grooves 13 extending transversely thereof and opening at their narrower edges to the face of the base opposite that from which the legs 11 and 12 extend. The grooves 13 are disposed intermediate the length of the base but somewhat nearer the end carrying the leg 11 than the end carrying the leg 12, as is clearly illustrated in Figure 4.

A platform 14 extends from the side of the base remote from the legs 11 and 12 at the end of the base from which the leg 12 extends and is disposed substantially perpendicular to the adjacent face of the base and in longitudinal alignment with the leg 12. This platform 14 has a notch

2

15 extending inwardly from the edge thereof remote from the base 10 and terminating in a substantially circular inner end. Beveled grooves 16 and 17 are provided one along each side of the notch 15 and constitute a guideway, the portion of the notch 15 at the outer side of the platform 14 being somewhat narrower than the portion of the notch at the inner side of the platform, as is particularly illustrated in Figure 5, so that portions of the platform extend inwardly of the grooves at the outer side of the extension, as indicated at 18 and 19 in Figure 5.

15 A one piece slide block 20 having beveled slide edges is slidably received in the guideway provided by the grooves 16 and 17 and substantially fills the notch 15. This block 20 has an aperture 21 extending therethrough and provided at the inner side of the block with a screw threaded counterbore 22 which receives the screw threaded neck 23 of a collapsible tube 24 disposed against the adjacent face of the base 10, the sealing beam 25 at the closed end of the tube being received in a selected one of the grooves 13, as is particularly illustrated in Figure 4.

20 The block 20 is provided on its outer side with a boss 26 of cylindrical shape which eccentrically surrounds the aperture 21 and a marginally flanged closure cap 27 is rotatably mounted on the boss and retained thereon by suitable means, such as the snap ring 28. The closure cap 27 has an opening 29 therein which is registrable with the adjacent end of the aperture 21 when the cap is in a predetermined rotational position relative to the boss 26. The cap 27 is provided in the distal edge of its flange with a notch 30 of an arcuate extent materially less than the diameter of the flange and a pin 31 projects from the boss 26 into this notch to limit rotational movements of the cap relative to the boss. When the pin is at one end of the notch 30 the opening 29 in the cap registers with the aperture 21 in the boss and when the pin is at the other end of the notch the opening in the cap is out of registry with the aperture in the boss thereby closing the neck or spout 23 of the tube 24. Slide blocks having screw threaded recesses of different sizes therein may be provided to accommodate the dispenser to tubes having screw threaded necks of different sizes.

25 The base is provided with screw holes, as indicated at 32 and 33, disposed one adjacent each corner of the base and extending through the base and the corresponding legs 11 and 21 to receive screws, as indicated at 34 and 35, for attaching the base to a suitable support, such as a bath

room wall. The base is preferably secured to the wall in upright position with the leg 12 and projection 14 at the bottom of the dispenser and the leg 11 at the top so that the tube 24 is mounted in inverted position with its screw threaded neck at the bottom of the tube and threaded into the counterbore in the block 20.

A bracket, generally indicated at 40, of U-shaped cross section embraces the base 10 and has legs 41 and 42 extending past the respectively opposite side edges of the base and a bight portion 43 extending between the legs and transversely across the face or side of the base 10 remote from the legs 11 and 12 in spaced relationship to the adjacent side of the base. Rollers 44 and 45 extend between the legs 41 and 42 at the side of the base adjacent the legs 11 and 12 in spaced apart and substantially parallel relationship to each other and are journaled at their ends on the corresponding bracket legs. These rollers engage the adjacent face of the base 10 to support the bracket for movement longitudinally of the base.

A roller 46 larger than the rollers 44 and 45 extends between the legs 41 and 42 adjacent the bight 43 of the bracket and is journaled at its ends on the corresponding legs. This roller extends transversely of the face of the base 10 remote from the legs 11 and 12 in spaced relationship to this face of the base and is adapted to compress the collapsible tube 24 between itself and the face of the base against which the tube is disposed to force the contents of the tube out of the neck 23 of the tube and through the aperture 21 in the block 20 when the bracket 40 is moved along the base in a direction from the leg 11 toward the projection 14. The leg 11 is made separate and detachable from the base so that it can be removed for placing the bracket 40 on the base and removing it therefrom.

A handle 47 is joined at one end to the bight 43 of the bracket and projects from the bight of the bracket in a direction away from the base 10 of the dispenser.

A housing 50 of thin walled construction and of elongated, rectangular shape, has one open side receiving the base 10 and one open end receiving the base projection 14, as is clearly illustrated in Figures 4 and 5. The housing 50 overlaps the side edges of the base at its open end and the end edge of the base at which the leg 11 is disposed and has L-shaped notches, as indicated at 51 and 52 in Figure 2, opening to the edge thereof at the open side of the housing. These notches receive pins, as indicated at 53, 54, 55 and 56, projecting outwardly from the side edges of the base one near each end of each side edge and received in the corresponding notches to releasably secure the housing on the base, the housing being removed by first raising it slightly relative to the base and then moving it outwardly away from the base.

The housing overlaps the edges of the base projection 14 at the open end of the housing and is provided in its front wall with a longitudinally extending, medially disposed slot 57 through which the handle 47 extends and in its top wall with a depression 58 for receiving the bottom of a drinking glass.

Notched formations 60 and 61 project outwardly one from each side of the casing 50 below the pins 53 and 54 to receive tooth brushes and support them on the housing as shown in Figure 3.

The invention may be embodied in other specific forms without departing from the spirit

or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims, are, therefore, intended to be embraced therein.

What is claimed is:

1. A paste dispenser comprising a base member of elongated rectangular shape having legs extending transversely thereof and projecting substantially perpendicularly from one side one at each end thereof and having spaced apart grooves extending transversely intermediate the length of the other side thereof, said grooves being undercut and having their narrower edges opening to said other side of the base and adapted to selectively receive the closure bead at the closed end of a collapsible tube and said base having screw holes extending therethrough and through said legs one adjacent each corner of said base, said base also having a platform projecting substantially perpendicularly from one end thereof in a direction opposite the adjacent leg and provided with a notch extending inwardly from the end thereof remote from said base and grooves extending one along each side of said notch providing a guideway, a slide block slidably mounted in said guideway and filling said notch, said block having an aperture extending therethrough and provided at one side of said block with a screw threaded counter bore adapted to receive the screw threaded neck of a collapsible tube, a boss projecting from the other side of said block in surrounding relationship to said aperture, a closure cap rotatably mounted on said boss and having a opening therein movable into and out of registry with the adjacent end of said aperture, a U-shaped bracket embracing said base and having legs extending one past each side edge of said base and a bight portion extending across said other face of the base and spaced therefrom, spaced apart rollers extending between said legs and journaled thereon in engagement with said one side of said base, a roller extending between and journaled on said legs adjacent said bight portion for compressing a collapsible tube against said other side of the base, a housing detachably secured to said base in covering relationship to said other side of the latter and to said bracket and the last mentioned roller and having a longitudinally extending slot therein, and a handle joined at one end to the bight portion of said bracket and extending through the slot in said housing.

2. A paste dispenser comprising a base member of elongated rectangular shape having legs extending transversely thereof and projecting substantially perpendicularly from one side one at each end thereof and having spaced apart grooves extending transversely intermediate the length of the other side thereof, said grooves being undercut and having their narrower edges opening to said other side of the base and adapted to selectively receive the closure bead at the closed end of a collapsible tube and said base having screw holes extending therethrough and through said legs one adjacent each corner of said base, said base also having a platform projecting substantially perpendicularly from one end thereof in a direction opposite the adjacent leg and provided with a notch extending inwardly from the end thereof remote from said base

and grooves extending one along each side of said notch providing a guideway, a slide block slidably mounted in said guideway and filling said notch, said block having an aperture extending therethrough and provided at one side of said block with a screw threaded counter bore adapted to receive the screw threaded neck of a collapsible tube, a boss projecting from the other side of said block in surrounding relationship to said aperture, a closure cap rotatably mounted on said boss and having a opening therein movable into and out of registry with the adjacent end of said aperture, a U-shaped bracket embracing said base and having legs extending one past each side edge of said base and a bight portion extending across said other face of the base and spaced therefrom, spaced apart, rollers extending between said legs and journaled thereon in engagement with said one side of said base, a roller extending between and journaled on said legs adjacent said bight portion for compressing a collapsible tube against

5 said other side of the base, a housing detachably secured to said base in covering relationship to said other side of the latter and to said bracket and the last mentioned roller and having a longitudinally extending slot therein, and a handle joined at one end to the bight portion of said bracket and extending through the slot in said housing, said housing having one open side receiving said base and open end receiving said 10 platform.
